UNITED STATES PATENT OFFICE

WILLIAM FISHER AND CHARLIE SMITH, OF BRADFORD, ENGLAND

AUTOMATIC RELEASING WRENCH

Application filed May 23, 1929, Serial No. 365,257, and in Great Britain June 28, 1928.

This invention relates to the construction of a tool for the weighting or tightening of rollers, and refers more particularly to the rollers connected with spinning and drawing machinery, but may be used for other purposes such as winding clocks, gramophones, or adjusting shock absorbers.

At the present time the usual method of adjusting the roller of spinning frames is by means of wing nuts, which apply pressure through a spring on to the arbor of the rollers. No indication of the amount of pressure is given, and an uneven contact between the rollers often results, which is detrimental to the fibres as they are being spun, more particularly as fluted bottom rollers are used. There is also, by using our apparatus, less wear on the friction driven top roller which may considerably affect the power taken to drive the spinning frame.

It is our object to replace the wing nuts by ordinary nuts, and construct a tool for tightening or winding purposes, which will supply the desired amount of pressure to each and every roller, independent of any variation that may occur in the roller springs, and that when such pressure has been reached the handle of the tool will disengage from its actuating position and apply no further pressure. We may however adapt the tool to operate the usual wing nuts.

In describing our invention in detail reference is made to the accompanying sheet of drawings, similar letters indicating similar parts, in which,

Fig. 1 represents a side elevation of the hereinafter described tool (partly in section).

Fig. 2 represents a plan looking from the top (also partly in section).

Fig. 3 represents a plan of a nut engaging member referred to.

Figs. 4 and 5 are respectively a partly sectional side view and a transverse sectional view of a box wrench constituting an element of the improved device;

Fig. 6 is a side view of the wrench operating handle illustrating one form of claw member;

Fig. 7 is a view similar to Fig. 6 but show-

ing a modified form of the claw member; and

Figs. 8 and 9 are views similar to Figs. 4 and 5 respectively, but showing a box wrench adapted for use with the claw member shown in Fig. 7.

To carry our invention into effect we mount on a suitable socket member or the like A a loose bush B, having a pair of perforated lugs or ears B' extending radially therefrom, said lugs being spaced apart to receive between them a claw like member C of a spring actuated handle C'. Within the barrel C² we insert a spring S terminating at one end in or bearing on a nose N which is in contact with a lug L projecting from the loose bush B, and at the other end are means for adjusting the tension of the said spring to apply whatever pressure is desired, comprising a screw threaded stud D operating within the barrel C² and which is provided with an indent or like D' to receive a suitable tool passed through an aperture C³ in the barrel closure member C⁴.

The claw like member C passes through the gap between the lugs B' on the bush B to which it is pivotally attached at B² and engages with a slot A' in the socket member A².

In operation, the tool having been set to the desired pressure is placed on the desired nut and the handle turned in the direction of the arrow in Fig. 2. When the desired pressure, which has been applied on the roller spring by the turning of the nut, becomes equal to that pre-arranged by the adjustment of the spring S in the handle C' of the tool, the nose N of the spring becomes compressed or is pushed inwards by the lug L on the bush and the claw like member C is released from the box key barrel A².

Further turning of the handle will produce no winding effect due to the disengagement of the claw.

Figs. 1, 2, 3, 4, 5, and 6 represent one form and details of parts referred to. In Figs. 7, 8, and 9 details are shown of an alternative form where the box key barrel A² and its slot A' vary slightly to receive a claw like member C^x, Fig. 7, carried by the handle C' 100

which varies slightly from that shown in Figs. 1 and 6.

It will be noted that while the handle C' is pivotally attached to the loose bush B its movement is limited by the lug L which is of such a construction and in such relationship to the handle or its nose as will permit of the claw like member being free of the box key at the desired time.

10 In some forms the spring mechanism might be carried by the lug L but this is not preferred as limitation of spring adjustment would ensue.

The socket member may be adapted to fit 15 nuts or other turnable members which may vary in shape.

We claim:

1. An automatic releasing wrench, comprising a rotatable nut-engaging member, a bushing encircling said member and mounted for rotation thereon, a handle pivotally secured to said bushing and having a claw adapted to engage said nut-engaging member thereby to rotate the same, and adjustable spring-pressed means between said handle and bushing and adapted to cause the release of said claw from said nut-engaging member when the turning pressure on said member is equal to the spring pressure.

30 2. An automatic releasing wrench, comprising a rotatable nut-engaging member, a bushing encircling said member and mounted for rotation thereon, a tubular handle provided with an offset extension pivotally secured to said bushing and having at its free end a claw adapted to engage said nut-engaging member thereby to rotate the same, a member longitudinally slidable in said handle and normally projecting therefrom in a direction approximately parallel with said claw, a tension spring disposed in said handle and adapted normally to maintain said slideable member in projected position, a stop member carried by said bushing in the path 40 of projection of said member, and means for adjusting the tension of said spring.

3. An automatic releasing wrench, comprising a rotatable nut-engaging member, a bushing mounted for rotation on said member and having a pair of radially extending spaced apart lugs, a tubular handle provided with an offset extension pivotally secured between said lugs and having at its free end a claw adapted to engage said nut-engaging member thereby to rotate the same, a member longitudinally slidable in said handle and normally projecting therefrom in a direction approximately parallel with said claw, a tension spring disposed in said handle and adapted normally to maintain said slidable member in projected position, a lug extending radially from said bushing at right angles to said pair of lugs, a stop member carried by said lug in the path of projection of said

member, and means for adjusting the tension of said spring.

In testimony whereof we have signed our names to this specification.

WILLIAM FISHER. 70
CHARLIE SMITH.
